UNITED STATES PATENT OFFICE.

WILLIAM MATHER, OF MANCHESTER, COUNTY OF LANCASTER, ENGLAND.

MACHINE FOR PRINTING SAMPLES ON TEXTILE FABRICS.

SPECIFICATION forming part of Letters Patent No. 339,448, dated April 6, 1886.

Application filed September 4, 1885. Serial No. 176,137. (No model.) Patented in England April 26, 1884, No. 6,838.

To all whom it may concern:

Be it known that I, WILLIAM MATHER, a subject of the Queen of Great Britain, residing at Manchester, in the county of Lancaster, England, have invented a new and useful Machine for Printing Samples on Textile Fabrics, (for which I have obtained a patent in Great Britain, No. 6,838, bearing date April 26, 1884,) of which the following is a specification.

My invention relates to improvements in printing samples or patterns on textile fabrics of designs from the engraved copper rollers used in printing-machines.

15 The process of "sampling" is at present extremely costly, as the same trouble and care must be taken in adjusting the printing-machine to obtain one or two yards of printed cloth as a sample from one or a set of engraved 20 copper rollers as are required for printing any number of pieces.

It is essential in calico printing that one set of engraved copper rollers making up one design should, by the use of different colors and 25 combinations, produce a great variety of effects. A separate trial must be made for each effect, and each trial involves a readjustment of the machine for the sake only of "striking off" one or two yards of cloth; hence great 30 delay and cost are incurred, and fewer samples or combinations are made than are possible and desirable if the process of sampling were inexpensive and simple.

The principal object of my invention, therefore, is to simplify and cheapen the process of sampling; and I attain this object by constructing a special machine for the purpose, wherein I am enabled to print samples of designs from the engraved copper rollers without 40 the necessity of first mounting the rollers on solid mandrels, and then putting them into the ordinary printing-machine.

And in order that my invention may be fully understood and readily carried into effect, I will describe the accompanying sheet of drawings, in which—

Figure 1 is a side elevation, and Fig. 2 a front elevation, of the machine for printing patterns or samples.

50 The cloth to be printed is stretched with the requisite tension round a large "bowl" or roller, *a*, as in an ordinary calico-printing

machine, the shaft of the roller *a* being supported in adjustable bearings *a'*, secured to two arms, *a''*, pivoted at *a''* to the standards of 55 the frame *b*, and at their outer ends jointed to rods *c*, by which they are connected to horizontal levers *d*, pivoted at *d'* to the frame *b* and weighted at *d''*. The pivoted levers *d* are operated by means of rods *e*, which have a 60 vertical reciprocating motion, and are secured below to the levers *d*, and carry at their upper ends anti-friction bowls *e'*, which rest upon and are operated by cams *f*, keyed to a cam-shaft, *g*. A spur-wheel, *g'*, is fixed on the cam-shaft 65 *g*, and is driven by a pinion, *h'*, secured on the driving-shaft *h*, which receives its revolving motion by means of a clutch, *i*, free to slide on a feather-key bedded in the shaft *h*, and moved by a forked lever, *i'*, into or out of 70 gear with clutch teeth formed on the boss of the driving-pulley *h''*, which is loose on the shaft *h*, and is driven by the strap *h''*. The forked ends of the lever *i'* rest in a groove in the clutch *i*, and the lever is secured at the 75 other end to a shaft, *i''*, which may be turned in either direction by a hand-wheel, *i''*. The rods *e*, therefore, always receive their vertical reciprocating motion whenever the clutch *i* is engaged with the clutch teeth on the driving-pulley *h''*, and the cam-shaft *g* revolves, and as 80 one of the rods *e* is slotted at *e''* to admit one end of a lever, *j*, pivoted at the other end, *j'*, to the frame *b*, this lever *j* is also actuated as the rods *e* rise and fall.

85 To the lever *j* is jointed one end of a rod, *k*, the other end of which is jointed to one end of a lever, *l*, fulcrumed at *l'*. Also fulcrumed at *l'* is a clutch-lever, *m*, the forked ends of which rest in a groove in a double clutch, *n*, 90 mounted and free to slide on a feather-key in a shaft, *o*, and engage with one or other of two bevel-wheels, *p* *p'*, loose on the shaft *o*, and both gearing into a carrier-wheel, *q*, fixed on a stud, *q'*, which is supported in a bearing in an arm or bracket, *q''*, carried by the frame *b*.

95 On the boss of the bevel-wheel *p* is secured the spur-wheel *r*, which is geared with and receives motion from the spur-wheel *g'*, which is driven by the pinion *h'*, as already described, whenever the clutch *i* is engaged with the driving-pulley *h''*, and in this manner whenever the spur-wheel *r* is driven the bevel-

wheel p revolves with it, and by means of the carrier-wheel q drives the bevel-wheel p' in the opposite direction. The shaft o is supported in suitable bearings in the frame b , and has keyed on its inner end a spur-wheel, s , which gears into the spur-wheel t , secured to the shaft of the roller a , and so drives the roller a in one direction, when the clutch n is in gear with the bevel-wheel p and in the opposite direction when the clutch is engaged with the wheel p' .

Fixed on the shaft of the roller a is a pulley, z , which is driven by a strap from a pulley, z' , on a counter-shaft, z^2 , to turn the roller a and bring onto the latter a fresh supply of cloth for printing another sample after a pattern has been completed. The engraved copper roller u is supported at each end on a pair of anti-friction rollers, v , free to revolve in bearings v' , secured to a transverse beam, v^2 , which is bolted to the frame b . The position of the engraved roller u is adjusted circumferentially by the use of a pitching pin or pointer, u' , and the engraver's pin-mark on the roller and endwise by screws w , which pass through side plates or brackets, w' , and have plates w^2 secured to their inner ends. These plates w^2 bear against the ends of the engraved roller u , and when the roller is in the proper position for printing it is secured in its place by the lock-nuts w^3 .

To give the color to the engraved roller u , a small color-box, y , with a "furnishing roller" revolving inside is carried by a bracket secured to the side plates, w' , and a "doctor" or cleaning blade for removing the surplus color is also employed.

The drawings represent the various parts in the position they occupy when the roller a is raised out of contact with the engraved copper roller u and the machine is at rest. When the clutch i is moved by means of the hand-wheel i^3 into gear with the clutch-teeth on the revolving pulley h^2 , the shaft h and pinion h' revolve, and motion is given to the wheel g' , and thus to the cam-shaft g . The cams f turn with the shaft g in the direction indicated by the arrows, Fig. 1, thus allowing the weighted levers d to draw down the rods e and anti-friction bowls e' , and as the rods e are drawn down the end of the lever j , resting in the slot e^2 , is depressed, thus actuating the rod k , lever l , and clutch-lever m , and moving the clutch n into gear with the revolving wheel p . In this manner motion is transmitted by the clutch n to the shaft o and spur-wheel s , and so by the wheel t to the roller a . As the clutch n is moved into gear with the wheel p in the manner described, the connecting-rods c , which are actuated by the movement of the weighted levers d , raise the outer ends of the arms a^2 , and so bring the roller a into contact with the engraved roller u , and as the roller a turns it drives the engraved roller u by friction, and the pattern is thus printed on the cloth stretched round the roller a . As long as the clutch i is in gear with the

driving-pulley h^2 , and the motion of the shaft g continues, the cams f alternately rise and allow the rods e to be lowered, by which means the clutch n is moved automatically from the wheel p to the wheel p' , as already described, and the motion of the roller a and other parts of the machine is reversed, the roller a being raised out of contact with the engraved copper roller u and turned back to the exact position from whence it started.

If the design requires more than one engraved copper roller, the second one is placed on the anti-friction rollers v , the first roller, u , being lifted out of the machine. The second roller is adjusted by means of the pitching-pin u^2 , as before described, to the exact position to fit its engraved figure into the impression taken from the first roller, and color from a fresh box is supplied to the roller. The roller a is then lowered by the arms a^2 , and the partial revolution is again made, as before, to print from the engraved roller. A third engraved copper roller may be treated in a similar manner, and so on to any number. On each return or reverse motion of the roller a it revolves the exact distance, as in printing; but when the pattern is completed the return is double or more, the roller a being driven by the pulley z , so that a fresh surface of cloth may be brought into position ready for printing from another set of rollers or different colorings off the same rollers.

The simplicity of adjustment of the rollers one after the other to fit exactly, the absence of the ordinary printing-machine and large color-box, and the rapidity with which the motions are automatically made in printing and reversing, enable a large number of combinations and colorings to be made, and many patterns or samples produced in a short time and with a small quantity of cloth as compared to that required in the usual way in the ordinary printing-machine.

Having thus stated the nature of my invention, and described the manner of performing the same, I declare that what I claim as my invention, and desire to secure by Letters Patent of the United States, is—

1. In a sample-printing machine, the combination, with the pivoted sample-roll arms and the driving mechanism of the sample-roll, substantially as described, of the cam mounted on a shaft geared to the driving-shaft and the weighted pivoted rod-connections, substantially as described, of said arms actuated by said cams, together with the driving-shaft, reversing-gear, and the pivoted rod-connections between said latter gear and the said weighted rod-connections, substantially as and for the purpose set forth.

2. In a sample-printing machine, the combination, with the engraved circumferentially-adjustable roll, of the sample-roll and mechanism for automatically raising and lowering the latter roll alternately and for reversing its motion, substantially as described.

3. In a sample-printing machine, the com-

5 bination, with the engraved roll circumferentially adjustable by the pitching pin or pointer and rotatably supported, of the sample-roll mounted to have an automatic alternately rising and falling motion, and to be reversed in its rotary motion, substantially as and for the purpose set forth.

4. In a sample-printing machine, the combination, with the pivoted sample-roll-supporting arms, of the pivoted weighted rod-connections, substantially as described, and the cam mounted on a shaft geared to the driving-shaft, and the rod-connection between the cam and the weighted rod-connection, substantially as and for the purpose set forth.

10 5. In a sample-printing machine, the combination, with the pivoted sample-roll arms, the pivoted weighted rod-connections, sub-

stantially as described, the driving-wheel with its clutch, the cam with its shaft geared to the 20 driving-shaft, and the gear-shifting mechanism, substantially acting in conjunction with the sample-roll shaft, and connected to a lever with the free end resting in a slot in a rod acted upon by said cam, and connected to the 25 said weighted rod-connection, substantially as and for the purpose specified.

The foregoing specification of my new and useful machine for printing samples on textile fabrics signed by me this 12th day of August, 30 1885.
